Attorney.

UNITED STATES PATENT OFFICE.

THEODORE J. ZOELLER, OF NASHVILLE, TENNESSEE, ASSIGNOR TO THE DAVIDSON LOCK COMPANY, OF SAME PLACE.

PERMUTATION-LOCK.

SPECIFICATION forming part of Letters Patent No. 633,711, dated September 26, 1899.

Application filed July 3, 1899. Serial No. 722,699. (No model.)

To all whom it may concern:

Be it known that I, THEODORE J. ZOELLER, a citizen of the United States, residing at Nashville, in the county of Davidson, State of Tennessee, have invented certain new and useful Improvements in Permutation-Locks; and I do hereby declare the following to be a full, clear, and exact description of the invention, such as will enable others skilled in the art to 10 which it appertains to make and use the same.

This invention relates to keyless permutation-locks for use upon doors, drawers, trunks, and closures generally requiring such fastenings. The preferred construction contemplates the employment of suitable dial-knobs, 15 dials, rotary notched and gated tumbler-disks, a reciprocating fence-frame, fences moving therewith, a locking-bolt, and an eccentric for throwing both the bolt and frame 20 aforesaid when the relative position of parts will permit.

The invention may be said, then, to have for its object the arrangement and combination of component parts herein shown and described for the purpose of producing a simple, 25 inexpensive, and durable construction whereby a locking-bolt may be quickly actuated or securely retained in a locked or unlocked position against the efforts of unauthorized persons.

The invention will be hereinafter more particularly described, and pointed out in the claims following.

In the accompanying drawings, which form 30 part of this specification, Figure 1 represents a face view of my improved lock, showing the face-plate, dial-knobs, dials, a bolt-actuating knob or handle, and one end of the locking-bolt. Fig. 2 is a reverse or interior plan 35 view of the invention, illustrating the tumbler-disks, fence-frame, click or tension springs, a cam for reciprocating said frame, and a fragment of the locking-bolt. Figs. 3 and 4 are side and end elevations, respectively, of parts illustrated by Fig. 1. Figs. 5 and 6 are detached detail views in plan, showing, respectively, the fence-frame and the locking-bolt. Fig. 7 is a plan view of one tumbler-disk detached.

Reference being had to the drawings and letters thereon, A indicates the face-plate of

the lock, through which project the arbors a a of rotatable dial-knobs B B, the latter each having a flanged base b b, upon which are suitable degree-marks adapted to rotate with said 55 flanged knobs and to coöperate with an index point or mark C, fixed upon the exposed surface of the lock. Upon the inner end of arbors a a are tumbler-disks D, mounted to rotate with said arbors and their respective 60 knobs B and configured by a series of equidistant peripheral notches c for the purpose of coöperating with click-springs d, fixed to the face-plate A, as indicated by Fig. 2. These disks D also have a radial gate E for admission of a fence at times when the combination is on, as will later appear, and surrounding their centers are a series of key-seats e, one of which receives a key or pin projecting from the end of arbor a to retain it in one 70 of several positions with relation to said arbor and knob, thus providing for changes of combination.

Rising from the inner surface of face-plate A are lugs f f and g g, serving to guide a 75 fence-frame F in its reciprocal movement, as also a locking-bolt G, the latter retained in addition by a bridge H, supported upon the lugs g g. At its outer end frame F is provided with oppositely-extending arms I I, each 80 terminating in a fence h, held normally in engagement with notches c of disks D by the action of a leaf-spring J, as shown by Fig. 2, or adapted to be thrown thereby into gates E when the combination is properly set. 85

The opposite or inner end of frame F is broken by an irregular opening, as K, into which projects a cam L, secured to and moving with a bolt-knob M, projecting from the face of plate A, as shown by Figs. 1, 3, and 90 4, said cam L being most clearly shown by Fig. 2. Said cam has a hammer-head i, by which the frame is engaged at its shoulders j or j and projected against action of the spring J as occasion may require. At the innermost extremity of the opening K is formed a central lug k, which also coacts with the head i of cam L at times when the combination is off. At such times said lug obstructs the passage of the cam-head, and thereby 95 blocks all movement of the main locking-bolt G, as will now appear. 100

The inner end of bolt G is broken by a transverse slot l, through which projects at all times an eccentric-pin m, rising from the surface of cam L and serving to throw or retract the bolt with each rotation of the bolt-knob M unless such rotation is positively obstructed by the lug k when the frame F is projected.

Having thus described the invention in its preferred form of construction and arrangement of parts, its operation, briefly stated, is as follows: Presuming for purposes of illustration that the combination is off, fences h h will then be held in engagement with two of the notches c c by action of spring J, but can be forcibly disengaged therefrom by a partial rotation of knob M, causing the head i of cam L to engage one of the shoulders j of frame F to advance it. Under these conditions, however, the cam L aforesaid cannot be rotated in the reverse direction for the reason that its head i would instantly engage the lug k within opening K of frame F, serving as a stop, and it being impossible thus to rotate the cam bolt G, controlled thereby, is locked in a projected or withdrawn position, according to circumstances. Fences h h having been withdrawn from disks D D, as stated, the latter may be rotated by the agency of knobs B B in the usual manner until gates E E are in alinement with said fences. By action of spring J the entire frame F is now advanced, and as a consequence the lug k, at the innermost extremity thereof, is withdrawn beyond the rotary path of cam L. Rotation of said cam past the lug k takes with it the eccentric-pin m, bearing in slot l of bolt G, the latter being accordingly shot forward or withdrawn, according to the direction of rotation. Thus it will be observed that the bolt G may be actuated and locked in either position by operation of knobs B B and M entirely without the aid of a detached key, and its action, owing to the structural arrangement of the lock, is rendered peculiarly sensitive and efficient under all conditions.

Having thus described the construction of my invention, its use, and general operation, I claim and desire to secure by Letters Patent—

50

1. In a permutation-lock the combination with a face-plate, of rotatable gated tumbler-disks, a reciprocating fence-frame and fences, a locking-bolt, and a knob-actuated cam for throwing both the frame and bolt dissimultaneously and also retracting the bolt, substantially as described.

2. In a permutation-lock the combination with a face-plate, of rotatable gated tumbler-disks, a reciprocating fence-frame and fences, a locking-bolt, a knob-actuated cam for throwing said frame, and an eccentric-pin upon said cam for operating the bolt aforesaid, substantially as described.

3. In a permutation-lock the combination with a face-plate, of rotatable gated tumbler-disks, a reciprocating fence-frame and fences, a locking-bolt, a knob-actuated cam within the confines of said frame for throwing it, a lug upon said frame for obstructing the path of said cam, and an eccentric-pin upon same cam for operating the bolt aforesaid, substantially as described.

4. In a permutation-lock the combination with a face-plate, of rotatable tumbler-disks, a spring-pressed reciprocating fence-frame having oppositely-disposed arms each bearing a fence, a locking-bolt, a knob-actuated cam for advancing said frame, a lug upon the frame for obstructing the path of said cam, an eccentric-pin upon same cam having a slotted connection with bolt aforesaid to operate it in both directions, substantially as described.

In testimony whereof I affix my signature, in presence of two witnesses, this 27th day of June, 1899.

THEODORE J. ZOELLER..
